UNITED STATES PATENT OFFICE.

ANTHONY J. BAULIG, OF ROME, NEW YORK, ASSIGNOR TO ROME METALLIC BEDSTEAD COMPANY, OF ROME, NEW YORK, A CORPORATION OF NEW YORK.

BUFFING-MACHINE.

1,086,698.

Specification of Letters Patent. Patented Feb. 10, 1914.

Application filed July 12, 1913. Serial No. 778,788.

To all whom it may concern:

Be it known that I, ANTHONY J. BAULIG, a citizen of the United States, residing at Rome, county of Oneida, State of New York, 5 have invented certain new and useful Improvements in Buffing-Machines, the following being a full, clear, and exact disclosure of the one form of my invention which I at present deem preferable.

10 For a detailed description of the present form of my invention, reference may be had to the following specification and to the accompanying drawings, which illustrate my invention, wherein—

15 Figure 1 is a side view of my machine and Fig. 2 a vertical section thereof.

My invention relates to a machine for producing on brass bedsteads what is known as a "velvet" finish which has heretofore been 20 produced only by hand. In that finish there is on the surface of the brass a slight trace of lines running circumferentially around the tube and while it can be produced on a straight length of tube by putting the tube 25 in a lathe and applying an abrading such as emery cloth to it as it rotates, yet in brass bedsteads the tube must be bent, previously to its being polished or finished, into the yoke form required for the end frame of the 30 bedstead, and after being so bent or shaped it can not be swung in a lathe, hence this particular finish has always been produced by hand.

35 My invention resides in a rotating ring carrying within it a tubular buffing device and rotated by an external belt. Thus as the ring and buffing device rotate, the tube to be finished can be introduced axially into the buffing tube and, without being itself 40 rotated, can be passed slowly through the said tube which produces on its surface the velvet finish above described. Moreover, the emery cloth within the buffing tube is so mounted on a yielding support or backing 45 of felt that the bent or elbow portion of the tube can also pass through it, even if the bend includes a curve of 90 degrees, and the bent or curved part will receive the same finish as the straight portion.

50 Referring to the drawing, A is a ring or annulus having a reduced portion A¹ on each side thereof forming a hollow or open journal mounted to rotate in bearings B, B. The outer periphery of ring A is slightly

55 crowned to give it a pulley surface for a belt F by which it is rotated. Within the ring A is mounted a two-part holder C, C¹, each part being provided with ears c, c by which the two halves may be screwed together. The holder is removable sidewise 60 from the ring A which has a horizontal groove a on each side into which the ears c c of the holder may pass. Screws D, D¹ pass radially through the ring A into the holder to center it in the ring while allowing it some play.

65 G is a layer of thick felt cloth within the holder and H is a layer of emery cloth or other abrader within the felt. By removing the holder and separating its two halves C, C¹ the felt and emery cloth may be bent 70 into tubular form and laid between C and C¹ which will then be screwed together and thereby have an adequate hold on the felt and emery cloth. The holder will then be 75 inserted in ring A and secured therein by the screws D, D¹ so that as the ring is rotated by belt F it will carry with it the holder C, C¹ together with the tubular felt and emery cloth secured in the holder. Then as the 80 brass tube E is inserted axially into the ring it will enter the buffing tube and the emery cloth will bear thereon and by virtue of its rotation will produce on the surface of the tube the desired finish. When the bend or 85 elbow of the tube is reached the felt will yield sufficiently to allow it to pass through and be acted on by the emery cloth in the same way as the straight portion.

90 What I claim as new and desire to secure by Letters Patent is:

1. A buffing machine comprising a ring or annulus open at both ends, journal bearings therefor outside of the axial opening therethrough, and means for securing buffing material on the inside of the ring.

95 2. A buffing machine comprising a rotating ring or annulus open at both sides, journal bearings therefor outside of the axial opening therethrough, and a buffing tube 100 therein provided with a yielding backing.

3. A buffing machine comprising a rotating ring provided with an axially open journal and bearings therefor and an internal holder removable laterally through 105 the open journal.

4. A buffing machine comprising a rotating ring provided with an axially open jour-

nal and bearings therefor and an internal two-part holder removable laterally through the open journal.

5. A buffing machine comprising a rotating ring provided with a hollow journal and bearings therefor of a holder within the ring, an abrader carried by the holder and a yielding support for said abrader.

10. A buffing machine comprising a rotating ring provided with a hollow journal and bearings therefor of a removable holder within the ring, means for securing it centrally therein, and a tubular abrader carried by said holder.

15. 7. A buffing machine comprising a ring provided with a hollow journal and bearings therefor of an operating device applied to

the outside of the ring and a removable and yielding tubular buffer in the ring in line with the hollow journal.

20

8. A buffing machine comprising a rotating ring having a hollow journal and bearings therefor of a removable two-part holder within the ring, means for securing said holder in said ring and a tubular abrader 25 having a yielding backing mounted between the two parts of said holder.

In witness whereof I have hereunto set my hand, before two subscribing witnesses, this 30th day of June, 1913.

ANTHONY J. BAULIG.
